UNITED STATES PATENT OFFICE.

GEORGE M. LAUB, OF NEW YORK, N. Y., ASSIGNOR TO EXCELLA PATTERN COMPANY,
OF NEW YORK, N. Y.

GARMENT OR DRESS PATTERN.

Application filed December 22, 1925. Serial No. 76,946.

This invention relates to garment or dress patterns such as are usually made of tissue paper and also to the method by which such patterns may be produced.

5 It is particularly well adapted for use in connection with the production of patterns of which large quantities are to be made, and which are printed on large sheets with symbols to indicate the cutting, notching 10 and perforating operations to be performed, together with clear instructions to be followed by the purchaser of the pattern when it is put into actual use.

These pattern sheets may be printed in the 15 usual manner from curved plates on presses constructed for the purpose, a master pattern having been first prepared with a due regard for economy in arranging the various sections on the sheet and a proper consideration for the selection and placing of 20 indicating symbols and instructions to insure correct performance of all the operations to follow.

I am familiar with what has been put on 25 the market in this art, and am aware of the previous patents which have issued upon patterns of this general type, but all of these previous devices have certain objections which I have endeavored to overcome.

30 In connection with tissue paper patterns there has always been difficulty in stacking large quantities of the printed blanket sheets so that all the printed lines in the stack would be in accurate register. Where the 35 printed lines have indicated the outlines upon which the garment sections are finally to be cut by the user of the pattern and a margin outside of the said printed lines has been allowed to remain on the printed sheets 40 until removed by the user, cutting the material and the paper pattern simultaneously along the said printed lines, the material beneath the paper pattern is not visible and absolute accuracy is impossible because of

45 the tendency of the material to creep and shift. With my pattern the material is always visible on the cutting line. Furthermore, after my blanket sheets have been cut into sections there are no printed outlines 50 visible, the edges of the sections indicating the cutting lines. If a pattern section shows a printed cutting line with a margin of paper outside which is only cut away by the user of the pattern, it is apt to confuse

such user as to which is the true line on 55 which the material is to be cut.

In another type, only the perforation and notch indicators with the general instructions for the user are printed on the blanket sheets which makes it necessary to 60 form the stacks for cutting, position the master pattern on the top sheet of the stack, and then mark on the latter the outlines of the sections, and the symbols for the notches and perforations for the guidance of the 65 cutter.

The blanket sheets for the pattern disclosed in this application are ready for the cutting operation when they are stacked after printing, and when cut, no printed 70 section outlines appear, as the margin allowed between the cutting guide and the cutting knife is ample to compensate for any slight deviations in the stacking.

Other advantages and details appear in 75 the following specifications, and are shown in the drawings, in which:—

Fig. 1 is a fragmentary view of a pattern sheet.

Fig. 2 is a view of one of the pattern sections.

Fig. 3 shows a stack of pattern sheets on a band saw table.

In printing the pattern sheet 5, as shown in Fig. 1, the outline 6 is printed about one-half inch outside of the real pattern outline 10, upon which the garment is to be cut. Simultaneously with the printing of the said outline 6, notch marks 7, perforation indicators 8, and instructions for use 9, are 85 90 printed on the sheet 5.

The said notch marks 7 may consist of a small indicator for the guidance of the operator and for the perforation indicators 8 a small letter "S" signifies a small perforation, the letter "M" indicates a medium sized perforation, and the letter "L" indicates a large perforation.

In Fig. 2 the completed cut out pattern section 11 is shown with the cut notches 12 100 and the perforations 13.

After the patterns are printed in full size, as indicated in Fig. 1, they are stacked for cutting on a table provided with a band saw 14 on either side of which a guide 15 is 105 mounted about one half inch away from the cutting edge of the said saw, so that the operator may direct the stacked sheets against

the said cutting edge with the printed line 6 running directly under the outside guide, which will cause the knife to cut the said sheets along the line 10 one half inch inside 5 the line 6.

It has been found that the use of a stationary guide produces the best results as compared with the use of a movable cutter as a guide.

10 In the use of this method a plate for every size of each pattern will be required, but the expense involved thereby is slight as compared with the economy resulting from the fact that the pattern sheets are ready for 15 the cutter as they leave the press and no indicating of the cutting lines, notch and perforation indicators is required.

As is obvious, these pattern sheets may be cut by hand when desired, as well as with a 20 power band saw, it being necessary merely for the cutter to cut along a line one half inch inside the printed line 6.

I do not desire to limit myself strictly to the preferred form of pattern shown here-

with, as there are various modifications 25 thereon which embody the invention without departing from the scope thereof.

I claim:—

The method of producing garment patterns which consists in printing on pattern sheets perforation indicators, notch indicators, instructions for the use of the pattern, and lines to be followed by a guide for a cutter, the said lines being positioned on the said pattern sheet outside of and parallel to 30 the outlines of the sections into which the pattern sheet is to be divided; and subsequently dividing the said pattern sheets into sections by passing them into relation with a guide and a cutter, the said guide traveling 35 along the said lines printed on the pattern sheet and the said cutter dividing the pattern sheet into sections, the outlines of which are cut inside of and parallel to the said 40 printed lines on the pattern sheet.

In testimony whereof I have hereunto affixed my signature.

GEORGE M. LAUB.
